POSITION INDICATOR PANEL FOR ELEVATORS

Morrison John Brounn, Flushing, N.Y., assignor to Otis Elevator Company, New York, N.Y., a corporation of New Jersey

Continuation of design applications Ser. No. 412, and Ser. No. 413, Jan. 3, 1966. This application June 26, 1967, Ser. No. 8,916

Term of patent 14 years

Int. Cl. D14—99

U.S. Cl. D72—1

FIG. 1

FIG. 2

FIG. 1 is a perspective view of a position indicator panel for elevators showing one form of my design wherein a row of keyhole elements are present below the central opening in the panel; and

FIG. 2 is a perspective view of the position indicator panel for elevators showing a second form of my new design wherein the keyhole elements have been omitted and the central opening is larger.

The representative indicia seen in the drawing figures is for illustrative purposes only.

This application is a continuation of design applications Serial Nos. 412 and 413, each filed Jan. 3, 1966, and each abandoned.

I claim:

The ornamental design for a position indicator panel for elevators, substantially as shown and described.
